UNITED STATES PATENT OFFICE.

HAMILTON E. SMITH, OF FITCHBURG, MASSACHUSETTS.

IMPROVEMENT IN MACHINES FOR PRESSING CLOTHES.

Specification forming part of Letters Patent No. 139,201, dated May 20, 1873; application filed January 8, 1873.

To all whom it may concern:

Be it known that I, HAMILTON E. SMITH, of Fitchburg, in the county of Worcester and in the State of Massachusetts, have invented a new and Improved Machine for Pressing and Smoothing Clothes and other Articles; and I do hereby declare the following to be a full, clear, and exact description thereof, which will enable those skilled in the art to make and use the same, reference being had to the accompanying drawing forming part of this specification, in which drawing—

Figure 1 represents a plan or top view of this invention. Fig. 2 is a longitudinal section of the same. Fig. 3 is an end view of the same.

Similar letters indicate corresponding parts. This invention consists in the combination of two endless aprons, one of which extends round a tension-roller and a large central roller, which is partially surrounded by a series of small pressing-rollers, round which the second apron is stretched, and which are adjustable toward and from the central roller, and geared together with the same in such a manner that, if the machine is set in motion in the proper direction and the articles to be pressed are placed upon the upper branch of the receiving-apron, (which extends around the central roller,) said articles are carried in between the receiving-apron and the pressing-apron, which extends round the pressing-roller, and, as they are carried through between the central roller and the pressing-roller, they are pressed and smoothed, while the aprons keep them in the proper position. The pressing-apron also serves to discharge the articles after the same have been pressed.

In the drawing, the letters A A designate two standards or frame-pieces, which form the bearings for a shaft, B, on which is mounted the central roller C, and also for the gudgeons of a series of pressing-rollers, D. The standards A A are provided with arms a a, furnished with slots b b to receive the journal-boxes c c of a roller, E, which I term the tension-roller of the receiving-apron. Said journal-boxes c c are exposed to the action of screws d d, which serve to draw the same outward. The receiving-apron F is stretched

round the central roller C and the tension-roller E, and by adjusting the boxes c c in their slots the tension of the said apron is regulated. The pressing-rollers D have their bearings in boxes e, which are adjusted toward and from the central roller by means of set-screws f, and all the pressing-rollers are geared together with the central roller, as shown in Fig. 3, so that they revolve with the same superficial velocity. With the pressing-rollers is combined a tension-roller, G, which has its bearings in slides g, that are adjustable by set-screws h, said slides being dovetailed into the standards A A. H is the pressing-apron, which extends round the pressing-rollers and round the tension-roller G, as shown in Fig. 2.

By adjusting the pressing-rollers, the pressing-apron can be brought to bear with more or less power upon the receiving-apron, and if the central roller is turned in the direction of the arrow marked on it in Fig. 2, and the articles to be pressed are spread on the upper branch of the receiving-apron, said articles are carried in between the two aprons, and, after having passed through between the pressing-rollers and the central roller, they are discharged over the tension-roller G upon a table, I, which is secured between the standards A A.

The central roller receives its motion from a shaft, J, with which it is geared together by cog-wheels i j, and the shaft J is driven by belt and pulley, or in any other desirable manner.

The aprons F and H are by preference made of India rubber, cloth, or other soft and elastic material, and as these aprons carry the articles to be pressed through between the pressing-rollers and the central roller, said articles are securely retained in the required position, and they are prevented from getting wrinkled or from being injured by direct contact with the metallic rollers.

The articles to be pressed can be readily and conveniently adjusted on the receiving-apron while the same is in motion, and a machine for pressing and smoothing clothes is obtained which is convenient in its operation, simple and durable in its construction, not liable to get out of order, and capable of pro-

ducing the desired effect with little trouble or loss of time. The effect of this machine may be improved by heating the roller C. What I claim as new, and desire to secure by Letters Patent, is—

1. The combination of a receiving and of a pressing apron, the former being stretched over a central roller and over a tension-roller, and the latter over a series of pressing-rollers arranged round the central roller and geared together with the same, substantially in the

manner and for the purpose herein shown and described.

2. The discharge-roller G, combined with the pressing-apron H, receiving-apron F, and table I, substantially in the manner and for the purpose set forth.

HAMILTON E. SMITH.
